UNITED STATES PATENT OFFICE.

ROSENETTA HART, OF PORT JEFFERSON, NEW YORK.

FLY-PAPER HOLDER.

1,132,007.

Specification of Letters Patent. Patented Mar. 16, 1915.

Application filed April 29, 1914. Serial No. 833,263.

To all whom it may concern:

Be it known that I, ROSENETTA HART, a citizen of the United States, residing at Port Jefferson, in the county of Suffolk, State of New York, have invented certain new and useful Improvements in Fly-Paper Holders; and I do hereby declare the following to be a full, clear, and exact description of the invention, such as will enable others skilled in the art to which it appertains to make and use the same.

This invention relates to improvements in sticky fly paper holders.

The principal object of the invention is to provide a device of simple construction which will hold one or more sheets of sticky fly paper, the holder being capable of being suspended in an upright position.

Another object is to provide a device for holding the fly paper in vertical position, means being provided for collecting the gum which drops from the paper.

Other objects and advantages will be apparent from the following description, when taken in connection with the accompanying drawings.

In the drawings: Figure 1 is a front elevation of the device. Fig. 2 is a vertical section on the line 2—2 of Fig. 1. Fig. 3 is a horizontal sectional view through the device showing two sheets of paper thereon. Fig. 4 is a top plan view of the device.

Referring particularly to the accompanying drawings, 10—10 represent uprights which are connected at their upper ends by a cross member 11. The lower ends of these uprights are secured in the bottom of a trough 12, these parts being preferably made of tin or other like metal. Secured at their opposite ends to the trough in the bottom thereof and to the transverse member 11 are the vertical parallel wires 13. Formed longitudinally in parallel relation in the transverse member 11, and on either side of the points of attachment of the upper ends of the wires are the elongated slits 14. The member 11 is somewhat longer than the width of a sheet of sticky fly paper, the slots being in length approximately the same as the width of the paper, so that one mar-

ginal end of a sheet of sticky fly paper may be inserted through one of the slots and suspended therefrom. To hold the upper ends of the paper within the slots, the said ends are bent over the upper member 11, or the paper may be pulled up through the slots until the gummed part engages with the edges of the slot. This latter method will cause the paper to readily stick. It will of course be understood that the sticky side of the paper is disposed away from the wires, the device being particularly adapted for holding two sheets of paper arranged back to back with the wires 13 extending therebetween. Carried by the member 11 is a ring 15 by means of which the frame may be suspended from the ceiling or other high point.

For adapting the device to set in a vertical position on a table or mantel, I detachably secure to the bottom of the trough an elongated plate 16 which forms a base. This base may be removed when the device is to be suspended by the ring. The wires will prevent the paper swinging back and forth and the trough will catch the drippings of the gum from the paper. When the papers are full of flies, they may be easily removed and new sheets inserted in the slots 14.

What is claimed is:

A fly paper holder comprising a trough member, uprights extending vertically from within the trough, a transverse member connecting the upper ends of the uprights and formed with longitudinal parallel slots for the reception of marginal ends of fly paper, flexible elements connected at their opposite ends to the bottom of the trough and to the transverse member between the slots, and a removable base member carried by the trough to permit the device to extend in a vertical position.

In testimony whereof, I affix my signature, in the presence of two witnesses.

ROSENETTA HART.
